UNITED STATES PATENT OFFICE

148,181

DESIGN FOR A RAZOR BLADE STROP

Eric T. New, New York, N. Y., assignor, by mesne assignments, to Louis Stern, New York, N. Y.

Application June 11, 1946, Serial No. 130,607

Term of patent 14 years

(Cl. D37—1)

To all whom it may concern:

Be it known that Eric T. New, a citizen of the United States and resident of New York city, in the county of New York, State of New York, has invented a new, original, and ornamental Design for a Razor Blade Strop, of which the following is a specification, reference being had to the accompanying drawing, forming part thereof, in which

Fig. 1 is a perspective view showing the top and leading end of the razor blade strop embodying my new design, and

Fig. 2 is a perspective view showing the bottom side and rear or handle end view thereof.

The blade shown in the broken lines is for the purpose of illustration.

I claim:

The ornamental design for a razor blade strop, as shown.

ERIC T. NEW.
